UNITED STATES PATENT OFFICE.

PETER EBNER, OF COLUMBUS, OHIO.

METALLIC CEILING OR SHEATHING.

No. 879,248.

Specification of Letters Patent.

Patented Feb. 18, 1908.

Application filed December 7, 1907. Serial No. 405,492.

To all whom it may concern:

Be it known that I, PETER EBNER, a citizen of the United States, residing at Columbus, in the county of Franklin and State of Ohio, have invented certain new and useful Improvements in Metallic Ceilings or Sheathing, of which the following is a specification.

My invention relates to the improvement of metallic ceilings or sheathing and the objects of my invention are to provide an improved construction of metallic sheathing or ceiling panels wherein is embodied improved means for locking the panels of each row into engagement with each other; to so construct and arrange the locking means as to admit of the lock connection between the panels being readily produced either before or after the panels are united with the furring strips or supporting framework; to provide improved means for connecting the panel supporting framework with metallic beams such as are usually used in the construction of vaults or other fire-proof structures and to produce other improvements the details of which will be more fully pointed out herein-after.

These objects I accomplish in the manner illustrated in the accompanying drawing, in which:

Fig. 1 is an underside view of four ceiling panels having my improved construction, Fig. 2 is an enlarged sectional view on line $x-x$ of Fig. 1, showing in addition thereto a continuation of the section through the corner plate or "cove" and through a portion of one of the wall panels, Fig. 3 is a view in perspective illustrating the means which I employ for connecting the furring strips with metal ceiling beams, Fig. 4 is a face view showing a portion of a furring strip and means connected therewith for securing the same to a wall, Fig. 5 is a detail view in perspective of the furring strip attaching device shown in Fig. 4, Fig. 6 is a detail sectional view on line $y-y$ of Fig. 1, and Fig. 7 is an underside view of the outer portion of one of the ceiling panels.

Similar numerals refer to similar parts throughout the several views.

1 represents sheet metal panels of that character which are designed to be used in the construction of sheet metal ceilings or side walls, these panels being cut and stamped to the required sizes and suitably embossed or ornamented when desired. In the construction of each of the panels 1, one side

thereof is bent rearward or upward forming an edge tongue or flange 1^a, which in its outer portion is curved inward and thence outward as indicated at 1^b. The opposite 60 edge of each of the panels 1 with the exception of those panels which lie adjacent to the sides of the room and which I have given the additional numeral of 1^c in the drawing, is formed with an upwardly projecting portion which is bent downward upon itself to form a loop which is indicated at 2. This elongated loop projection is of such width in its lower portion as to present a comparatively narrow entrance slit and in the joining of two adjacent panels, the curved tongue 1^b of one panel is forced through said narrow opening and into the loop of the adjacent panel, thereby springing the outer member of the loop slightly outward and 70 causing the outer edge portion of the tongue to engage the inner surface of the loop in the upper portion of the latter. This engagement in conjunction with the pressure on the tongue of the outer member of the loop, 80 serves to form a desirable detachable locking connection of adjoining panels, which locking connection can be produced either before the panels are placed in their position against the ceiling framework or afterward.

It will be understood that the above described method of connecting the panels can be carried out through one row of panels at a time and that the adjoining rows of panels when similarly united are connected with 90 the first mentioned row by causing their adjacent edges to overlap each other in the manner indicated in Fig. 6 of the drawing, said overlapping portions being suitably nailed to the furring strips 3 which are secured at proper intervals to the ceiling framework. It will be observed by reference to Fig. 7 of the drawing, that the loop 2 is not of such length as to extend to the ends of the panel (which is also true of the 100 tongue 1^b) thus providing a space between the ends of the loops and tongues of two adjoining panels for the free passage of the furring strip.

In the construction of the furring strips 105 3, I ordinarily employ the usual wooden bars or frame pieces, the same being first covered with a sheet metal sheathing or casing as indicated at 4.

As indicated in Figs. 1 and 2 of the drawing, the outer edges of those ceiling panels 1^c which are nearest the side walls of the

room, are formed without the loop 2, the edge portions of said panels being in the nature of a horizontal flange such as is indicated at 1^d. These flanges 1^d are connected 5 with a suitable filling strip 5 which is suitably secured to the undersides of the furring strips and which has its outer portion connected, as shown in Fig. 2 of the drawing, with the upper portion of an inclined corner 10 plate or "cove" 6. This cove plate or strip is intended to cover the junction of the ceiling and side walls of a room and has its lower end portion turned outwardly as indicated at 6^a, said outturned portion being suitably 15 secured to the tops of vertical or side wall furring strips 7 to the outer faces of which are secured side wall metallic panels 8. In attaching the furring strips to the side wall of the room, I employ at desirable intervals 20 attaching devices such as are indicated at 9 in Figs. 2, 3 and 5. This attaching device or clip consists in a sheet metal body having opposing tongues 9^a which are formed with forwardly bent side wings 9^b. The clip 9 25 further consists in oppositely projecting central wall attaching tongues 9^c. The body of the clip 9 is adapted to engage the rear side of a furring strip, while the sides of the latter are embraced by the wings 9^b. The 30 tongues 9^c are adapted to receive attaching nails which may be driven into the side wall or its framework and the central portion of the clip body may, if desired, be nailed to the rear side of the furring strip. The side 35 wall furring strips, as prescribed for those of the ceiling, are covered with a sheathing or casing such as indicated at 7^a.

In Fig. 3 of the drawing, I have shown a portion of a metallic ceiling beam which is 40 indicated at 10, this beam being of that character which is ordinarily employed in the construction of the ceiling framework of a vault or other fireproof structure. Owing to the difficulty of attaching the furring 45 strips to the flanged lower side of those metal beams by nailing, I employ the attaching clamps which are indicated at 11. Each of these clamps comprises a channel-like body preferably of sheet metal, the downturned 50 opposing sides 11^a of which have formed in corresponding ends, recesses 11^b which are adapted to receive the greater portion of one of the flanges 10^a of the beam 10. The clamps 11 are strengthened by having the

central portion of their upper sides bent upwardly to form a rib or channeled portion which is indicated at 11^c. The side pieces 55 11^a of the clamp are secured by nails 12, or by other suitable attaching devices, to the sides of the covered furring strip 3 and when 60 two of these clamping pieces are thus secured to the furring strip in such position that the oppositely projecting portions 10^a of the base flange enter the recesses 11^b, it is evident that the furring strip will be securely 65 anchored to the metal beam.

In connecting a furring strip with two other furring strip sections which extend at right angles therewith, I may employ the construction also illustrated at the left in 70 Fig. 3, in which the ends of the two transverse furring strips which I have indicated at 3^a and which abut against the sides of the strip 3, are supported in the oppositely projecting socket members 13 of a coupling body 75 14. This coupling body is formed of sheet metal and is provided at its central portion with projecting channel-like members 15 which are adapted to embrace the bottom and opposite sides of the strip 3 to which said 80 coupling body is secured.

What I claim, is—

1. In a metallic ceiling and sheathing construction, the combination with interlocked ceiling panels, and means for attaching said 85 panels to a ceiling framework, of a corner or "cove" member, vertical side wall furring strips, the upper ends of which meet and support the lower portion of said cove member, and ceiling filling strips which connect the 90 outer ceiling panels with said cove member.

2. In a metal ceiling and sheathing construction, the combination with metal ceiling beams having flanged bases, and furring strips intersecting said ceiling beams at right 95 angles, of metal clamping members comprising channel shaped bodies formed with end recesses in their side portions, said end recesses being adapted to receive the base flanges of said metal beams, and the sides 100 of the clamping bodies being adapted to be secured to the sides of the furring strips.

In testimony whereof I affix my signature in presence of two witnesses.

PETER EBNER.
